REFRESHMENT BOOTH FRONT

Le Baron E. Stockford, Foxboro, Mass.
(Westboro State Hospital, Westboro, Mass.)

Filed May 6, 1960, Ser. No. 60,477

Term of patent 7 years

(Cl. D13—1)

The figure is a front elevation view of a refreshment booth front showing my new design.

The rear not shown is plain. The article has an inappreciable thickness and the face members on the front represent surface ornamentation.

I claim:

The ornamental design for a refreshment booth front, as shown and described.
